(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface, showing my new design.

The outer broken lines in the figures show a display screen and form no part of the claimed design.

The broken line rectangles within the graphical user interface illustrate the bounds of the claimed design and form no part thereof.
